UNITED STATES PATENT OFFICE.

HERBERT ABRAHAM, OF NEW YORK, N. Y., ASSIGNOR TO THE RUBEROID CO., A CORPORATION OF NEW JERSEY.

ROOFING ELEMENT.

Application filed May 19, 1920. Serial No. 362,496.

To all whom it may concern:

Be it known that I, HERBERT ABRAHAM, a citizen of the United States, residing at the city, county, and State of New York, have 5 invented certain new and useful Improvements in Roofing Elements, of which the following is a specification.

This invention relates to improvements in manufacture of elements of the type having 10 spaced projections along their upper and lower edges.

The principal objects of the invention are to provide elements of such shape that they can be cut from a web of fabric without 15 waste, and laid to form a water-proof covering with a minimum amount of material.

I attain these objects, as well as others, by providing elements of novel configuration, having the characteristics hereinafter 20 described and pointed out in the claims.

The elements can be made, without waste of material, by means of a single cutter operating intermittently to cut a continuously moving web of material along a line extending 25 obliquely to the sides of the web.

In the accompanying drawings, illustrating the invention,

Fig. 1 is a plan view of a fragment of a web showing the manner of cutting the elements,

Fig. 2 is a plan view of a preferred form of elements,

Fig. 3 shows a plurality of the elements laid in overlapping courses; and,

Figs. 4 to 12 show several modified forms 35 of my element.

By referring to the drawings, it will be seen that the upper and lower edges 1 and 2 of the elements are alike in contour and are each formed of a broken line, that is, one 40 having alternating projections and indentations. The sides 3 and 4 are formed of straight, parallel, oblique lines, extending from an indented portion of one edge to a projected portion of the opposite edge.

The elements illustrated in the drawings are of the type known as "twin shingles," that is, one composed of two identical units forming an integral strip. It is to be understood that the elements may consist of a 50 single unit forming an "individual shingle" or they may be composed of any desired number of units to form "multiple shingle strips."

55 In each case the unit is characterized by

the fact that a series of imaginary lines connecting all corresponding points of the lower and upper edges, as for example, the points $a-a'$, $b-b'$, $c-c'$, $d-d'$, would be equal in length and would extend parallel to the oblique sides. This characteristic permits of both the upper and lower edges of the element being formed with a single cutter extending obliquely of the web.

A further characteristic of the unit is the fact that the vertical axis $x-x'$, through the center of the projections of the lower and upper edges, extends perpendicular to the horizontal axis $y-y'$. This provides elements which are symmetrical in shape and which when laid form a watertight roof covering of attractive and ornamental appearance.

Elements having the characteristics herein defined may be made in a variety of different designs by changing the contour of the upper and lower edges. For example, in Figs. 4 to 12 I have shown a variety of elements differing from each other in outline but all having the same general characteristics in that in each case a series of lines connecting corresponding points of the upper and lower edges 1 and 2 would be equal in length and parallel to the oblique sides 3 and 4, and in each case the axis $x-x'$ through opposite projections is perpendicular to the longitudinal axis $y-y'$.

Preferably the element is formed so that the vertical distance between opposite points at the widest part is substantially three times as great as that at the narrowest part. Elements having the characteristics and proportions hereinbefore described, when laid in overlapping courses as shown in Fig. 3, will require not more than 200 square feet of material to weatherproofly cover 100 square feet of roof area. To attain the greatest protection at the joints, the projections and indentations must be disposed in such relation to the oblique sides, that the joints will bisect the area composed of three thicknesses of the elements when laid.

In each case the elements are laid so that the projections along the lower edge of each course register with the innermost part of the indentations in the lower edge of the underlying course, and when thus laid the diagonal joints of adjacent elements in each course come between the elements of the underlying and the overlying courses and are

substantially covered by the elements of the overlying course. This provides an ornamental covering which is easily laid, and which provides adequate protection against 5 leakage at the joints.

In manufacturing the elements, I take a web of roofing material A, of any suitable width, and cut it at intervals by means of a cutter, whose axis extends obliquely to the 10 lateral edges of the web, as indicated by the dotted line 5 in Fig. 1, the shape of the cutting edge being such as to form elements of the character described. Each operation of the cutter simultaneously forms one edge of 15 an element and the opposite edge of the succeeding element. In this manner, with a single cutter, operating intermittently to cut a continuously moving web, I produce a series of elements without any waste of material 20 at the edges of the web or between successive elements. As the felt fibers of the roofing material run generally lengthwise of the web, fibers of the severed elements will extend obliquely to the axes of the elements, due to the fact that the said elements 25 are cut obliquely from the web. For economy of manufacture it may be desired to take a web of sufficient width to accommodate a plurality of units and then slit the 30 web parallel to its lateral edges, as indicated by the broken line 6, to produce elements of any desired multiple of units.

I am aware that prior to my invention shingles have been made with angular sides, 35 such, for example, as shown in Letters Patent No. 1,108,236, issued to H. M. Reynolds on August 25th, 1914, but I believe that I am the first to devise elements of such character that a succession of the elements can be cut 40 obliquely from a web of fabric, without waste of material.

What I claim is:

1. A roofing element having oblique parallel sides, and having its upper and lower edges composed of similar broken lines, the configuration of the element being such that all of the corresponding points of the upper and lower edges are equally distant when measured on lines parallel to the sides.
2. A roofing element having oblique parallel sides, and having its upper and lower edges composed of similar broken lines, the configuration of the element being such that all of the corresponding points of the upper and lower edges are equally distant when measured on lines parallel to the sides, the maximum vertical distance between the upper and lower edges being three times as great as that of the minimum distance.

3. A roofing element having oblique parallel sides and having its upper and lower edges each formed of uniform projections and intervening uniform indentations, the projections on either edge being identical in contour with the indentations of the opposite edge, all of the corresponding points of the upper and lower edges being equally distant when measured on lines parallel to the sides.

4. A roofing element having its sides 70 formed of oblique parallel lines each connecting a projection on one edge, with an indentation on the other edge, and having its upper and lower edges each formed of uniform projections and intervening uniform indentations, the projections on either edge corresponding in contour with the indentations of the opposite edge, all of the corresponding points of the upper and lower edges being equally distant when measured 80 on lines parallel to the sides.

5. A roofing element having oblique parallel sides, and having its upper and lower edges each formed of uniform projections and intervening uniform indentations, the projections on either edge being centrally disposed with respect to the projections on the opposite edge, all of the corresponding points of the upper and lower edges being 85 equally distant when measured on lines parallel to the sides.

6. The method of making roofing elements, each having its upper and lower edge formed of uniform projections and intervening uniform indentations, the projections on either edge being identical in contour to the indentations of the opposite edge, which consists in cutting a web of prepared roofing material intermittently at regular intervals corresponding to the width of the strips to be cut, along a single broken line extending obliquely across the web.

7. The method of making roofing elements, each having its upper and lower edges formed of uniform projections and intervening uniform indentations, the projections on either edge being identical in contour to the indentations of the opposite edge, which consists in cutting a web of prepared roofing material intermittently at regular intervals, corresponding to the width of the strips to be cut along a single broken line extending obliquely across the web, and cutting the web along straight spaced longitudinal lines extending parallel to the sides of the web to divide the strips into elements of desired lengths.

HERBERT ABRAHAM.
